UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

CROSS-WEAVING LOOM.

Application filed April 4, 1928. Serial No. 267,245.

This invention relates to leno or cross-weaving looms in which certain of the warp threads are crossed relative to others to produce a cross or marquisette weave.

5 In the patent to Alfred E. Stafford, No. 1,511,184, dated October 7, 1924, a loom of this general type is shown and described wherein the doup thread is controlled by a doup heddle having two legs adapted to be engaged by 10 lifter heddles on each shed formation to move the doup thread from the closed shed plane to the upper plane of the shed on each shed formation, and such action of the lifter heddles is controlled by suitable cam and treadle 15 mechanism at the lower part of the loom, whereby the lifter heddles are operated, first one and then the other, to raise the doup thread to the upper plane of the shed. Associated with each of the doup heddles and its 20 associated lifter heddles there is described in this patent a jumper heddle for controlling the jumper thread, and means are provided to positively move the jumper heddle from the closed shed plane to the lower plane of the 25 shed on each shed formation. This manner of controlling the heddles has proved to be effective and efficient, but since the jumper thread crosses over the doup thread at each 30 shed formation, the positive action of the jumper heddle is liable at times to put undue strain upon the jumper thread.

In accordance with the present invention, the jumper heddle is normally under the action of yielding means, such as a spring or 35 springs, for moving the jumper heddle and jumper thread to the lower plane of the shed on each shed formation, thereby obviating the undue strain that frequently occurs on the jumper thread or threads when the jumper 40 heddle is moved to the lower shed plane.

When, however, the jumper thread is crossed over or above the doup thread and the jumper heddle is under the influence of the 45 spring means for moving it to the lower plane of the shed, the doup thread is liable to retain the jumper heddle from its full downward movement under the spring acting means, although permitting such movement sufficiently for the formation of a proper shed. 50 Under these conditions, the flexible connection between the jumper heddle and its lifting means is liable to become slack, with the result that the flexible connection will at times fail to properly engage the guide over 55 which it passes, and, indeed, at times jump

entirely from such guide and cause improper loom operation.

In a loom of the general type hereinbefore stated, a doup heddle, two lifter heddles, and a jumper heddle constitute a unit, and the 60 lifter and jumper heddles are actuated in a two-to-one relation to always place the doup threads in the same plane of the shed and the jumper thread in the opposite plane of the shed on successive shed formations, and here- 65 after the action of the cross-weaving unit will be described, it being understood, of course, that any desired number of units may be employed in the leno or cross-weaving 70 loom.

One of the objects of the present invention is to obviate the objections incident to slackness in the flexible connection between the jumper heddle and its transmitter or lifting means during the idle stroke of the latter, 75 when the jumper thread is crossed over the doup thread and the jumper heddle is moved to the lower plane of the shed, and maintain such flexible connection taut, notwithstanding the fact that the jumper thread and consequently the jumper heddle may be prevented 80 from full lowered position by the doup thread.

The invention and new features thereof will best be made clear from the following description and the accompanying drawings of 85 one good form thereof.

In the drawings:

Fig. 1 is a perspective view of a leno or cross-weaving loom containing the present 90 invention;

Fig. 2 is an enlarged front elevation, with parts broken away, of the jumper heddle head motion; and

Fig. 3 is an enlarged side elevation of the 95 jumper heddle head motion with some of the parts shown in section.

In accordance with the present invention, the lifter heddles which are associated in pairs with the doup heddle are actuated positively by cam and treadle mechanism substantially as shown and described in the Stafford patent above mentioned, and consequently it is not herein deemed necessary to further describe this feature, but the jumper heddle in 100 the present invention is moved downwardly by the yielding action of spring means and in this respect differs from the loom shown and described in the Stafford patent.

In the Spofford Patent, No. 1,439,029, dated 110

December 19, 1922, the lifter and jumper heddles are each given their downward movements during the shedding operation by the contractile force of springs attached to the 5 heddles and to some fixed part.

The loom frame 1 may be of usual construction and have mounted thereon the usual crank shaft 2 for actuating the lay, and connected to the crank shaft 2 is a crank arm 3 10 having a pin and slot connection 4 with a rod 5 extending upwardly and connected at its upper end 6 to the head motion of the jumper heddle, and such parts as thus far described may be substantially the same as indicated 15 in the Stafford Patent, No. 1,511,184, hereinbefore mentioned.

Extending upwardly from the loom frame is the loom arch 7, above which projects an arm 8 for the support of the head motion. 20 Mounted in a suitable bearing 9 of the arm 8 is a stud or shaft 10 on which is mounted the actuator 11 which, as indicated in Fig. 1, is connected to the rod 5, whereby the actuator 11 is given its rocking movement upon the 25 stud or shaft 10.

The arm 11, as indicated in Fig. 3, has a sleeve portion 12 by which it is mounted for rocking movement on the stud or shaft 10, and extending from the actuator 11 is a projecting portion 13 which is adapted to engage 30 and operate the head motion for the jumper heddle, as will presently be described.

The head motion of the jumper heddle comprises a transmitter or rocker 14 which 35 may be appropriately mounted on the sleeve portion 12 of the arm 11 for rocking movement thereon. The transmitter 14 has a segment 15 adjustably connected thereto by means of a pin 16 and slot 17, whereby the 40 segment 15 may be properly adjusted upon the transmitter of which it forms a part.

Extending from the transmitter 14 is an arm 18 having a portion 19 adapted to be 45 engaged by the projecting portion 13 of the actuator during the active stroke thereof, whereby the transmitter may be moved from the crank shaft to lift the jumper heddle into the closed shed plane against the action of the jumper heddle depressing springs, as will 50 presently appear.

Secured to the segment 15 is a strap or flexible connection 20, a portion of which extends over the guide or pulley 21 mounted for turning movement upon a stand 22 rising from 55 the loom arch. The lower end portion 23 of the flexible connection 20 is secured to the jumper heddle frame 24 which is normally under the influence of springs 25 for effecting lowering movement of the jumper heddle 60 during the idle stroke of the head motion. As indicated in Fig. 1, the jumper heddle frame 24 carries the jumper heddle 26 having an eye 27 through which passes the jumper thread *a*, the lower end portion of the 65 jumper heddle 26 being secured to the lower

part 28 of the jumper heddle frame, which, as above stated, is under the influence of springs 25 for effecting lowering movement of the jumper heddle frame. It is to be understood, of course, that there may be any 70 number of jumper heddles 26 for the control of any suitable number of jumper threads, but only one is shown in Fig. 1 of the drawings, since the others will be merely duplicates thereof.

As hereinbefore stated, a unit of the leno or cross weaving mechanism comprises a jumper heddle and a doup heddle with which are associated two lifter heddles. The doup heddle 29 has the usual eye portion 30 through 80 which passes a doup thread *b*, and such doup heddle has the two leg portions 31 and 32 which are engaged by the associated pair of lifter heddles, substantially as more fully described in the Stafford and Spofford patents hereinbefore mentioned. The lifter heddle frames 33 and 34 have the usual lifter heddles 35, 36, each of which engages a downwardly extending leg of the doup heddle, whereby the doup heddle will be raised from the closed shed plane to the upper plane of the shed on each shed formation, substantially in all respects as more fully described in the 90 patents above mentioned.

Connected with each of the lifter heddle frames 33, 34 are the flexible connections or straps 37 and 38 which pass upwardly over suitable guide pulleys and are connected at their upper portions to the oscillating pulley 39. Where the loom contains a plural number of units constituted by a doup heddle, pair of lifter heddles and a jumper heddle, other straps of similar character will be connected to such heddles and pass upwardly about a guide pulley on the loom arch and 100 be secured at their upper ends to suitable pulleys, such as 40, in a manner similar to the same character of construction as indicated and described in the Stafford patent. The pulleys 39 and 40 are mounted upon the 110 rocking arm 41 which may be appropriately supported by the shaft or stud 10, as indicated in Fig. 3, the construction forming a compensating device for the proper formation of the shed as described in the Stafford 115 patent.

As hereinbefore stated, the head motion for the jumper heddle comprises the transmitter 14 and its associated segment 15, and during the active stroke of the actuator 11 120 the latter will engage the arm 18 of the transmitter in order to raise the jumper heddle into the closed shed plane. In the idle stroke of the actuator and transmitter it is desirable to maintain the flexible connection between the transmitter and jumper heddle in a taut condition in order that the 125 flexible connection may not become disengaged from its guide or pulley 21, and to this end the transmitter is provided with a stop 130

for arresting the idle stroke of the transmitter during the downward movement of the jumper heddle in response to its lowering springs.

- 5 To this end the arm 18, in the present instance, has the projecting portion 42 into which is threaded a stop 43 which may be held in adjusted position by a lock nut 44, and such stop is adapted to engage and be arrested 10 by a fixed part of the loom during the downward movement of the jumper heddle, thereby maintaining the flexible connection between the transmitter and jumper heddle taut, notwithstanding the fact that the doup 15 thread over which the jumper thread passes may prevent full lowering movement of the jumper heddle responsive to its lowering spring. In the present instance of the invention the stop 43 is adapted to engage the 20 edge portion 45 of the upwardly extending arm 8, as indicated in Fig. 1.

From the construction described it will be apparent that when the actuator 11 is moving in its active stroke to raise the jumper 25 heddle, it will engage the transmitter 14 and lift the jumper heddle to place the jumper thread in the closed shed plane, and on its idle or inactive stroke the actuator 11 will become disengaged from the transmitter 14 to 30 permit the stop 43 to arrest movement of the transmitter in its idle stroke, with the result that the flexible connection between the transmitter and jumper heddle will be maintained in taut condition notwithstanding that the 35 doup thread may prevent full lowering movement of the jumper heddle under the action of its lowering spring.

During the weaving operation one of the 40 lifter heddles will raise the doup heddle and consequently the doup thread controlled thereby from the closed to the upper plane of the shed, and substantially simultaneously therewith the jumper heddle will move the jumper thread, now crossed over the doup 45 thread, into the lower plane of the shed, and although the jumper heddle may not be fully depressed by its actuating springs and be held slightly raised by the sustaining action of the doup thread, the stop on the transmitter 50 will arrest the idle movement of the transmitter to maintain the flexible connection between it and the jumper heddle taut and without slackness.

The stop 43, as will be noted, is adjustable, and may be manipulated to arrest the transmitter during the lowering movement of the jumper heddle at a point in the downward movement of the latter, such that the flexible connection between the transmitter and the jumper heddle may always be maintained in taut condition.

What is claimed is:

1. In a leno or cross-weaving loom, the 65 combination of doup heddles and lifter heddles therefor, a jumper heddle, yielding

means normally acting to depress the jumper heddle, a head motion for the jumper heddle, a flexible connection between the head motion and jumper heddle, and a stop for the jumper head motion acting to maintain the flexible 70 connection taut when the jumper heddle is held raised by the crossed doup and jumper threads.

2. In a leno or cross-weaving loom, the combination of doup heddles and lifter heddles therefor, a jumper heddle, spring means normally acting to lower the jumper heddle, a head motion for raising the jumper heddle, a flexible connection between the jumper heddle and head motion, and a stop for limiting the idle stroke of the head motion to maintain the flexible connection taut when the jumper heddle is lowered by its normally 80 acting spring lowering means.

3. In a leno or cross-weaving loom, the combination of a doup heddle, two lifter heddles for operating it, a jumper heddle, a spring normally acting to lower the jumper heddle into the lower shed plane when the jumper thread is crossed over the doup 90 thread, a transmitter for lifting the jumper heddle, a flexible connection between the transmitter and jumper heddle, a guide for the flexible connection between the transmitter and jumper heddle, and a stop for limiting the movement of the transmitter as the jumper heddle is lowered by its spring and the threads are crossed that the flexible connection may be maintained taut.

4. In a leno or cross-weaving loom, the combination of a doup heddle, two lifter heddles for raising the doup thread into the upper shed plane on each shed formation, a jumper heddle, a spring normally acting to lower the jumper heddle when the jumper thread is crossed over the doup thread, a rocking transmitter for raising the jumper heddle, a flexible connection between the transmitter and jumper heddle, and means for limiting the movement of the transmitter 105 as the jumper heddle is lowered by its spring to maintain the flexible connection taut between the transmitter and jumper heddle.

5. In a leno or cross-weaving loom, the combination of a doup heddle and two lifter 115 heddles, a jumper heddle, a spring normally acting to lower the jumper heddle, a transmitter for raising the jumper heddle, a flexible connection between the transmitter and jumper heddle, an actuator for the transmitter, and a stop for limiting the idle stroke of the transmitter when the jumper heddle is lowered by its spring and the jumper thread is crossed over the doup thread that the flexible connection may be maintained taut as 120 the jumper heddle is lowered.

6. In a leno or cross-weaving loom, the combination of a doup heddle and two lifter heddles, a jumper heddle, a spring normally 130 acting to lower the jumper heddle, a trans-

mitter for raising the jumper heddle, a flexible connection between the transmitter and jumper heddle, an actuator for the transmitter, and a stop for limiting the idle stroke 5 of the transmitter when the jumper heddle is lowered by its spring and the jumper thread is crossed over the doup thread and means for adjusting the stop that the flexible connection may be maintained taut as the 10 jumper heddle is lowered.

7. In a leno or cross-weaving loom, the combination of a doup heddle and two lifter heddles, a jumper heddle, a spring for lowering the jumper heddle, a rocking transmitter 15 for raising the jumper heddle, a flexible connection between the transmitter and jumper heddle, an arm projecting from the transmitter, an actuator for engaging said arm to raise the jumper heddle, and a stop 20 for limiting the idle movement of the transmitter to maintain the flexible connection taut as the jumper heddle is lowered by its

spring and the jumper thread is crossed over the doup thread.

8. In a leno or cross-weaving loom having 25 a doup heddle, lifter heddles, a jumper heddle, and a spring for lowering the jumper heddle, the combination of a transmitter for raising the jumper heddle, a flexible connection between the transmitter and jumper 30 heddle, a guide for the flexible connection, an actuator for engaging the transmitter to lift the jumper heddle, and a stop for engaging a part on the loom frame for limiting the movement of the transmitter responsive 35 to the jumper heddle spring to maintain the flexible connection from becoming slack as the jumper heddle is lowered by its spring and the jumper thread is crossed above the doup thread. 40

In testimony whereof, I have signed my name to this specification.

HARRY A. DAVIS.
